UNITED STATES PATENT OFFICE.

CHARLES J. REED, OF PHILADELPHIA, PENNSYLVANIA, ASSIGNOR TO
REED-MORRILL ELECTRIC CO., A CORPORATION OF PENNSYLVANIA.

SPEED-CHANGING MECHANISM.

SPECIFICATION forming part of Letters Patent No. 758,474, dated April 26, 1904.

Application filed September 15, 1903. Serial No. 173,256. (No model.)

To all whom it may concern.

Be it known that I, CHARLES J. REED, a citizen of the United States, residing at Philadelphia, in the county of Philadelphia and State 5 of Pennsylvania, have invented certain new and useful Improvements in Speed-Changing Mechanisms, of which the following is a specification.

This invention is a mechanism for transmitting power from a driving to a driven shaft and enabling the speed of the driven shaft to be varied with reference to that of the driving shaft.

The mechanism comprises a double pulley, 15 which is placed between and bolted to pulleys on the driving and the driven shafts. The double pulley has two drums, each consisting of a set of radially-adjustable rim-sections and means for simultaneously moving either set 20 of rim-sections inwardly and the other outwardly, thereby contracting one drum and expanding the other.

Referring to the accompanying drawings, Figure 1 is a plan view of the double pulley, 25 with the parts at one side of a vertical axial plane in horizontal axial section. Fig. 2 is a transverse vertical section of the double pulley on the line II II of Fig. 1 with a portion broken away, and Fig. 3 is a transverse 30 vertical section on the line III III of Fig. 1.

The pulley 1 is carried by a shaft 2, journaled in bearings 3, and has plural drums, (shown as two in number,) each drum having movable rim-sections 4. The double pulley 35 comprises three rim-section-adjusting disks 5 6 7, which are keyed on a sleeve 8, revolvably supported on the shaft 2. The disks 5 6 are spaced apart to receive between them one set of rim-sections, and the disks 6 7 are spaced 40 apart to receive between them the other set of rim-sections. The disks 5 6 7 have in their opposing faces spiral grooves 9. The grooves in the disks 5 7 are cut in a contra-clockwise direction from the center to the circumference. 45 The grooves in both faces of the disk 6 are cut in a clockwise direction from the center to the circumference.

Between and closely adjacent to the grooved faces of the adjusting-disks are the rim-section-guiding plates 10 11 12 13. The plate 50 10 has a peripheral flange 10', which surrounds the edge of the adjusting-disk 5. The plates 11 12 have peripheral flanges 11' 12', which are secured together. The plate 13 has a broad peripheral flange 13', which carries 55 gear mechanism for adjusting the rim-sections. The plates 10 11 are rigidly secured on the flanged radially-slotted ends of a sleeve 14, which is revolvably supported on the sleeve 8 between the adjusting-disks 5 6. The plates 60 12 13 are rigidly secured on the flanged radially-slotted ends of a sleeve 15, which is revolvably supported on the sleeve 8 between the adjusting-disks 6 7. The flange 10' of the plate 10 is secured to the corresponding flange 65 16' of a plate 16 outside the adjusting-disk 5 and keyed to the shaft 2. Each of the plates 10 11 12 13 has a circular series of substantially radial equidistant slots 17, which receive and 70 guide the ends of the rim-sections 4. Each of the rim-sections 4 consists of a straight bar with a broad belt-receiving surface and having at each end teeth 18, which fit the spiral grooves 9 of the adjusting-disks. The rim-sections are so constructed that the bearing-surfaces 75 of the sections of each drum are equidistant from the axis of the pulley-shaft, notwithstanding the fact that each successive section enters the spiral groove at a somewhat greater distance from the center than the preceding 80 section. This result may be effected by cutting the teeth 18 in different positions on the sections of each drum.

It will be seen that the guide-plates 10 11 12 13 are rigidly connected together and to 85 the shaft by the plate 16, flanges 16' 10', sleeve 14, flanges 11' 12', and sleeve 15, so that rotation of the sleeve 8, carrying the adjusting-disks on the shaft, causes the teeth of all the rim-sections to move spirally in the several 90 grooves 9 and radially in the guide-slots 17. The rim-sections constituting one pulley-drum are thereby moved inwardly, decreasing the diameter of the drum, and the rim-sections of

the other set are simultaneously moved outwardly, increasing the diameter of the other drum.

The rotation of the sleeve 8 on the shaft to 5 adjust the drums may be effected by any desired mechanism. That shown comprises a gear 19, integral with the outer face of the adjusting-disk 7, and an engaging pinion 20, carried on the end of a shaft 21, which is revolu- 10 bly mounted in a block 22, bolted to the flange 13' of the guiding-plate 13. The outer end of the shaft 21 carries a pinion 42, engaging a worm 23, fixed on a shaft 24, which is also revolutely mounted in the block 22. The 15 inner end of the shaft 24 carries a bevel-pinion 25. Revolutely mounted on the projecting end of the pulley-shaft 2 is a sleeve 26, on the ends of which are keyed two bevel-gears 27 28, one at each side of the bevel-pinion 25. A pivoted 20 hand-lever 29, having a spring-pressed detent 30, engages eyes 31, projecting from the outer face of gear 28. The hand-lever serves to shift the sleeve 26 on the shaft 2 and to bring either bevel-gear 27 or 28 into engagement 25 with the pinion 25. When the detent 30 of the hand-lever is in engagement with the middle notch 32 of the arm 33, both gears 27 28 are held out of engagement with the pinion 25. When the lever is thrown to the left and 30 the detent engages the notch 34, the gear 27 is thrown into mesh with the pinion 25, thereby rotating the worm 23, pinions 42 and 20, and finally the gear 19, and thereby the three adjusting-disks. The simultaneous ro- 35 tation of these three disks relatively to the four guiding-disks simultaneously moves the rim-sections of one pulley-drum inwardly, decreasing the diameter of the drum, and the rim-sections of the other drum outwardly, in- 40 creasing its diameter. When the two drums have been adjusted to give the desired speed, the hand-lever is again thrown to its middle position. Movement of the hand-lever in the other direction until the detent 30 engages the 45 notch 35 brings the bevel-gear 28 into engagement with the pinion 25, thereby rotating the adjusting-disks in the opposite direction.

Various changes may be made in the mechanism shown and described. The sleeve car- 50 rying the adjusting-disks may be rotated by various devices—for example, those claimed in my applications, Serial No. 164,523, filed July 7, 1903, or Serial No. 167,450, filed July 29, 1903. The belt-receiving surface of the 55 rim-sections may be convex or concave. The guide-slots need not be radial, provided they cross the spiral grooves, and they may be slightly curved instead of straight. The spiral grooves may be of different form and pitch 60 from those shown. The pulley may have more than two drums, and the adjusting-disks may be grooved to effect any desired adjustment of the rim-sections of the several drums.

I claim—

1. A pulley having plural drums, each drum 65 having movable rim-sections, a tube revolu- bly mounted on the pulley-shaft, and three adjusting-disks fixed on said tube, as set forth.

2. A pulley having plural drums, each drum 70 having movable rim-sections, a tube revolu- bly mounted on the pulley-shaft, and three adjusting-disks having spiral grooves and fixed on said tube, as set forth.

3. A pulley having plural drums, each drum 75 having movable rim-sections, a tube revolu- bly mounted on the pulley-shaft, three adjusting-disks having spiral grooves and fixed on said tube, and means for rotating said tube on said shaft, as set forth.

4. A pulley having plural drums, each drum 80 having movable rim-sections, three adjusting- disks revolutely supported on the pulley-shaft, and four guiding-plates rigidly connected to said shaft, as set forth.

5. A pulley having plural drums, each drum 85 having movable rim-sections, three spirally- grooved adjusting-disks revolutely supported on the pulley-shaft, and four guiding-plates rigidly connected to said shaft and having slots crossing said spiral grooves, as set forth. 90

6. A pulley having plural drums, each drum having movable rim-sections, a tube revolu- bly mounted on the pulley-shaft and carrying three adjusting-disks, and guiding-plates rigi- 95 dly connected to said shaft, the guiding-plates of each drum being carried on the ends of a sleeve revolutely supported on said tube between two of said adjusting-disks, as set forth.

7. A pulley having plural drums, each drum having movable rim-sections, a tube revolu- bly supported on the pulley-shaft and carrying three adjusting-disks, and guiding-plates rigi- 100 dly connected to said shaft, the guiding- plates of each drum being carried on the ends of a sleeve revolutely supported on said tube between two of said adjusting-disks and the adjacent guiding-plates of the two drums being rigidly connected together at their peripheries, as set forth.

8. A pulley having plural drums, each drum having movable rim-sections, a tube revolu- bly mounted on the pulley-shaft and carrying three adjusting-disks having spiral grooves which engage the ends of each rim-section, 115 guiding-plates having substantially radial guide-slots for said rim-sections, the guiding- plates of each drum being carried on the ends of a sleeve revolutely supported on said tube between two of said adjusting-disks and the adjacent guiding-plates of the two drums being rigidly connected together at their peripheries, 120 and a plate fixed on the pulley-shaft and rigidly connected at its periphery to one of said guiding-plates, as set forth.

9. A pulley having plural drums, each drum having movable rim-sections, a tube revolu-

bly mounted on the pulley-shaft, and a disk having adjusting-grooves in its opposite faces and fixed on said tube, as set forth.

10. A pulley having plural drums, each drum having movable rim-sections, a tube revolvably mounted on the pulley-shaft, a disk having adjusting-grooves in its opposite faces and fixed on said tube, and means for rotating said tube on said shaft, as set forth.

11. A pulley having plural drums, each drum having movable rim-sections, a tube revolvably mounted on the pulley-shaft, a disk hav-

ing adjusting-grooves in its opposite faces and fixed on said tube, and guiding-plates rigidly connected at their peripheries and inclosing 15 said adjusting-disk, as set forth.

In testimony whereof I have signed my name to this specification in the presence of two subscribing witnesses.

CHARLES J. REED.
